Primary Examiner — Karen E Eldridge Powers

(57) **CLAIM**

We claim the ornamental design for a display screen with graphical user interface, as shown and described.

DESCRIPTION

FIG. 1 is a front view of a first embodiment of a display screen with graphical user interface;

FIG. 2 is a front view of a second embodiment of a display screen with graphical user interface;

FIG. 3 is a front view of a third embodiment of a display screen with graphical user interface;

FIG. 4 is a front view of a fourth embodiment of a display screen with graphical user interface;

FIG. 5 is a front view of a fifth embodiment of a display screen with graphical user interface;

FIG. 6 is a front view of a sixth embodiment of a display screen with graphical user interface;

FIG. 7 is a front view of a seventh embodiment of a display screen with graphical user interface;

FIG. 8 is a front view of an eighth embodiment of a display screen with graphical user interface;

FIG. 9 is a front view of a ninth embodiment of a display screen with graphical user interface; and,

FIG. 10 is a front view of a tenth embodiment of a display screen with graphical user interface.

The broken lines shown surrounding the display screen with graphical user interface are for the purpose of illustrating an article of manufacture on which the display screen with graphical user interface is provided; the broken lines shown within the bounds of the display screen with graphical user interface are for the purpose of illustrating portions of the article; the broken lines form no part of the claimed design.
